UNITED STATES PATENT OFFICE.

PAUL C. OSCANYAN, OF OCEANIC, NEW JERSEY.

GAME BOARD OR BULLETIN.

1,127,498.

Specification of Letters Patent.

Patented Feb. 9, 1915.

Application filed September 11, 1913. Serial No. 789,366.

To all whom it may concern:

Be it known that I, PAUL C. OSCANYAN, of Oceanic, in the county of Monmouth and State of New Jersey, have invented certain new and useful Improvements in Game Boards or Bulletins; and I do hereby declare the following to be a full, clear, and exact description of the invention, such as will enable others skilled in the art to which it appertains to make and use the same.

This invention relates to game boards or bulletins, designed to illustrate graphically, the progress of a game, such as base ball, by means of indicators representing the runners and the ball, which move over the surface of a miniature field and portray the actual movements of the ball and the runners in the sequence in which they occur.

This invention is designed particularly as an improvement on the construction disclosed in my application Serial Number 683,794 filed by me March 14th 1912. In the application above referred to the runners are mounted on sliding carriers, each of which moves back and forth between two bases, the runner members being in full view of the audience during the forward movement, and concealed from view during the return movement. Again in the prior application the representation of the ball at the front, has a movement the reverse of that of the ball control at the rear.

The object of the present invention is to provide improved means for actuating the runner members, and also improved means for actuating the ball member, and it consists in the parts and combination of parts and in the details of construction as will be more fully explained and pointed out in the claims:

In the accompanying drawings, Figure 1 is a view in front elevation of the bulletin board, part of the cover being removed, to show the endless chains, runner members and stop mechanism. Fig. 2 is a view in elevation of the rear of the board. Figs. 3 and 4 are enlarged views of the sprocket chains and wheels, and the stop mechanism for the several chains. Fig. 5 is a view in elevation of one of the reels for the flexible devices carrying the ball and ball control. Fig. 6 is a side view of the mechanism for moving the ball member outwardly away from the field. Fig. 7 is a view in elevation, partly in section, of a device for supporting the flexible member carrying the

ball and ball control, and which may be used instead of the reel shown in Fig. 5. Fig. 8 is a view of the chain between home plate and first base. Fig. 9 is a view of the second and third base chains. Fig. 10 is a view of the chain between third base and home plate. Figs. 11, 12, 13 and 14 are views of the brackets which carry the runner members. Fig. 15 is a view of one of the chain stops. Fig. 16 is a view of one of the chain cams. Figs. 17 and 18 are views in plan of the brackets shown in Figs. 12 and 13 respectively. Fig. 19 is a view of a bracket not provided with a stop. Fig. 20 is a plan view of one of the runner members. Figs. 21 and 22 show the runner members secured to their brackets, Fig. 23 is a view in section of the drive mechanism for the driving sprocket wheels 7. Figs. 24 and 24^a are views of the removable runner member and Fig. 25 is a view of the ball member, its flexible support and actuating cords.

1 is a supporting frame provided on one face with the representation of a base ball field and at its center with an opening through which the infield 2 shows, the latter being in a plane at the rear of the outfield, so that the runner members, which are in a plane at the rear of the outfield will show over the edge of the infield.

Secured to the rear side of the supporting frame 1, is the square frame 3. This frame 3 carries the infield 2, and when in place at the rear of the supporting frame 1, the infield 2 shows through the opening in the center of said supporting frame. In Fig. 1 the supporting frame is cut away in order to show the mechanism for actuating the runners, but this frame 1 covers the frame 3, with the margin of its opening approximately in line with the outer margin of the infield, but removed forwardly therefrom sufficiently to permit the runner members 4, which are at the rear of the frame 1, to project over the edge of the infield as shown in Fig. 1. Mounted in frame 3, is an inner frame 5, preferably made of metal, in which the sprocket wheels 7 and 7' are mounted. The sprocket wheels 7 and 7' are for the runner member carrying chains 8, 9, 10 and 11, the chain 8, being between the home plate and first base; the chain 9 between the first and second bases; the chain 10 between the second and third bases and the chain 11 between the third base and home plate.

Each chain is mounted on a driving sprocket 7 and on a loose sprocket 7' at the rear of the supporting frame 6, and the whole series of chains are actuated by the electric motor 9^a, the armature shaft of which is provided with a worm wheel 12 meshing with a gear 13. This gear is fixed to a shaft which carries a sprocket wheel 14 for the drive chain 14', the latter also passing around a sprocket wheel fixed to the shaft carrying the sprocket 6, so that when motor 9 is running, sprocket wheel 6 will be rotating. The axle of each idle sprocket wheel 7' is provided with a handle 7² by which it and its chain may be actuated for a purpose to be hereinafter described.

The sprocket wheels 7, two of which are adjacent the home plate and two adjacent the second base, are each fixed to a shaft 15, mounted in anti-friction bearings 16 carried by the inner frame 5. Each shaft also carries a sprocket wheel 17 loose thereon, and friction clutch members 18 and 19, between which the sprocket 17 is yieldingly clamped by the spring 20. Member 18 of the clutch bears against a shoulder on the shaft 15, which holds it against movement lengthwise the shaft. Both clutch members 18 and 19, for each driving sprocket wheel 7, are preferably provided with wearing faces 21, which may be renewed when worn, and one or both of said members, is fixed to the shaft 15 so as to rotate with it. An endless chain 22 is in mesh with a sprocket wheel fixed to the shaft of sprocket wheel 6, and also in mesh with the four loose sprockets 17 as shown in dotted lines in Fig. 1, so that the four loose sprockets 17 and sprocket wheel 6 are constantly rotated while the board is in use. As previously explained, there is a sprocket wheel 7 on each of the four shafts 15, and these four wheels 7 constitute the drive wheels for the four endless runner carrying chains 8, 9, 10, and 11. The other four sprockets 7', are idle wheels and are rotated by said chains.

In the operation of the apparatus the motor 9 is constantly running while the game is in progress, and transmits motion through drive shaft 14 to the sprocket wheel fixed to sprocket wheel 6, and to the endless chain 22, through sprocket wheel 6, hence it will be seen, from the manner in which the sprockets are connected, that, if there be no obstruction to the free movement of the chains 8, 9, 10 and 11, all four of them will be constantly in motion, but as they are normally restrained against movement by mechanism to be hereinafter described, and are only released to permit a runner to advance a base, the sprocket wheels 17 being positively driven by the motor 9^a, slip, or rotate on their shafts 15 without imparting any movement to said shafts. When however any one of the chains 8, 9, 10 or 11, is re-

leased from its stop mechanism, its sprocket 17 by its frictional contact with its clutch members, turns its shaft and rotates the sprocket 7 which, as before stated, is the drive sprocket for its runner member carrying chain.

The stop mechanism for the several runner chains, is best shown in Figs. 3 and 4, and consists of a casing 23 carrying a series of pivoted bell crank levers 24, 25, 26 and 27, 75 one for each runner chain, and a push button or finger piece 28, for each bell-crank lever. Each of the runner chains, which are shown in Figs. 8, 9 and 10, is provided with a series of stops, some of which, 29, 80 are longer than the others, 30. The endless chain 8, between the home plate and first base, shown in Fig. 8, is provided with two long stops 29 and one short stop 30; the endless chains 9 and 10 between the first 85 and second bases and between the second and third bases are alike, and each is provided with four long stops 29 and two short ones 30, and the chain between third base and the home plate is provided with four 90 long stops 29. Each of the four chains except the one between home plate and first base is also provided with a series of cams 31. The cam 31 and long stops 29, shown detached in Figs. 16 and 15, respectively, 95 are simply sides of links provided with the cam and stop shoulders, and the short stops 30 are all formed integral with the runner member carrying brackets 32, and 33, shown in Figs. 11 to 14 inclusive, and in Figs. 100 21-22. Each runner member bracket forms the side of a link as shown in Figs. 8 to 11, and they are so constructed that the brackets on the chains between home plate and first, and between second and third bases, will 105 support the runner members in a different plane from those on chains between first and second bases and third base and home plate, so as to permit the runner members to make the turns simultaneously over the sprockets 110 7 and 7' without colliding, hence on two oppositely disposed chains, low brackets 32 will be employed, and on the two other oppositely disposed chains, the higher brackets 33 are used, the low brackets 32, thus carrying their runner members 4 under or at the rear of the runner members 4 on the high brackets 33.

The chain 8 between home plate has one runner member 4 and three stops, two of 120 which are high and one low, and they are so located with relation to the runner member that they operate to hold the runner member concealed under the frame 1, or exposed over the home plate and over first 125 base. When the runner member is concealed, and also when it is over the home plate, the chain is blocked from movement by its long stops 29, one for each of said positions, and when the runner member is 130

over the first base, the chain is blocked by its single short stop 30. The chain 9, from first to second base, carries two oppositely disposed runner members 4, and has six 5 stops, two of which are short (30) and are integral with the runner brackets 32 or 33, as the case may be, and four of them are long (29). These stops are so located with relation to the two runner members 4 that 10 the chain 9 will be blocked by one of its long stops 29, when the runner members are concealed, and also when either runner member is exposed at first base, but when either runner member is exposed at second base. 15 the chain will be blocked by one of its short stops. This chain 9 also has a cam 31 in line with the first long stop 29 after the runner 4, which cam operates to release the chain between home plate and first base 20 when chain 8 has a runner on first base. As an illustration, a runner is exposed at first and the batter makes a base hit or is sent to his base. By now actuating the stop device to release the chain 9 between the first and 25 second bases, so as to carry a runner from the first to the second base, the movement of said chain 9, operates through its cam to release the chain 8 so as to carry the runner thereon back to a point adjacent the home plate.

The chain 10 between the second and third bases, is substantially identical with the one between first and second bases except that its runner carrying brackets are constructed to carry their runners out of the plane of the runners on the chains at end of same. It also has a cam 31 immediately in rear of its runner member carrying brackets, which actuates the stop mechanism to carry runner 40 exposed at second base back to its normal position of rest. The chain 11, between third base and the home plate has four high stops, there being no stops on the runner carrying brackets, as the runners on this chain never 45 stop over the home plate. Two stops hold the runners on third base and two hold them in their concealed position. This chain 11, also has a cam in rear of the first long stop immediately following each runner, for re-laying the runner on chain between second and third bases, when the runner is exposed at third base. The stop mechanism for the 50 chains 8, 9, 10 and 11, is actuated by a series of push buttons, which in the present 55 instance, are mounted in a casing 23 at the rear of the board adjacent the first base. This casing carries a series of bell-crank levers, each of which is actuated by a push button and each of which actuates the stop 60 mechanism of one runner member carrying chain. Bell crank lever 24 actuates the pitman 34 which is connected with stop lever 35 pivoted to the inner frame 5. This stop lever is provided with an arm the free end 65 of which rests in the plane of the stops 29 and 30 on chain 9, the spring 36 tending to normally hold said arm in the path of the stops. The lever 35, is also connected by pitman 37 with one arm of the lever 38, which latter is also pivoted to frame 5, and 70 is provided at the free end of its other arm with a shoe 39, which normally rests close up to the chain 10, in a plane in rear of the stops, but in the plane of the cams 31, so that as the chain moves its cam comes in 75 contact with the shoe 39, it turns lever 38, and the latter through pitman 37, moves lever 33 in a direction to disengage the end of the latter from the stops on the chain 9, and will disengage said stop providing it be 80 a short stop, but will not move the said lever a distance sufficient to release it from a long stop, the said lever being released from the long stops by the push button only. Bell crank lever 25 is connected by pitman 40 85 with the lever 41 pivoted to frame 5. One end of this lever rests in the path of the stops on the chain 8, and the other end is provided with a shoe 42 which rests close up to the chain 9, between first and second bases, and in the path of the cams on said chain. The bell crank lever 28, operates to disengage said lever 41 from either the long or short stop on chain 8, while the shoe 42 by the engagement therewith of the cams on chain 9, disengages said lever from the short stops on chain 8. Bell crank 27 is connected by pitman 43, with lever 44, one end of which is adapted to engage stops on chain 10, while the other end is provided with a shoe 45 adapted to be engaged by the cams on chain 11, so as to release chain 10 when the latter is held by a short stop. Lever 44 is normally held with its two ends close up to chains 10 and 11 by the spring 46. Bell 100 crank lever 26 is connected by pitman 47 to one end of the lever 48, the spring 49 tending to hold said end in the path of the stops on chain 11.

As previously explained, the endless chain 110 22 is constantly rotating during the progress of the game, and normally the four sprockets 17 on shafts 15, with which said chain engages, slip on these shafts, and there is a shaft 15 carrying sprocket and clutch mechanism for each sprocket wheel 7. The operation of this part of the mechanism is as follows: By depressing push button 28 engaging pitman 40, lever 41 will be moved to disengage it from one long stop 29, thus 115 permitting chain 8 to start. If the push button be instantly released, as it should be, lever 41 will move back into a position to engage the next stop 29, thus stopping the chain 8 with the runner member exposed at the home plate. If now the batter makes a hit, or is sent to his base, chain 8 is again 120 released by push button and lever 25 as previously explained, thus carrying the runner member to first base where it is stopped by 125 130

the short stop on the runner bracket engaging the free end of lever 41. By now pushing down on the push button 28 which actuates bell crank 24, chain 9 will be released thus permitting a runner member thereon to come into position over first base, and as it passes to its exposed position over the base, the cam 31 immediately behind the runner member on chain 9, engages shoe 42 and trips its lever thus releasing chain 8 and permitting it to carry its runner member back to a position adjacent the home plate, the runner member being concealed during the return movement. The runner on first, 15 is advanced to second, by actuating lever 35 through its pitman 34 and bell crank 24, it is advanced from second to third by actuating lever 44 through its pitman 43 and bell crank 27 and is advanced to home by actuating lever 48, through its pitman 47 and bell crank lever 26. In each instance after the runner reaches a base it is held by a short stop on its chain, so that it can be released by a cam and go back to its starting point, 25 when the runner it represents is advanced one base. When a runner member reaches a base it stays there exposed, until advanced, a base, at which time a runner on the chain next in advance takes its place, and releases the chain of the runner it has superseded, thus permitting the superseded runner to move out of sight. If the runner should be put out, its chain is released by its proper push button and is passed to the rear of the 30 supporting frame 1. If there should be a runner on first base and one on second base, and they should each be advanced a base this would be accomplished by actuating stop levers 35 and 44, simultaneously through their push buttons, bell cranks and pitmen. The push buttons should of course be released immediately after the chains start so that the runners will come to a stop immediately upon reaching the next base, 45 and the same is true with the other bases. If for instance a home run should be made, the stop mechanism controlling chain 8 would be first actuated to carry the runner to first base. Immediately upon reaching first base, the stop mechanism of chain 9 should be operated. This releases chain 9 and the cam thereon engaging shoe 42 on lever 41 moves same and releases chain 8, thus permitting it to carry its runner member back adjacent the home plate but not exposed over the same. As the runner member on chain 9 reaches second base, the stop mechanism of chain 10 should be operated, and as the runner thereon takes the place of the runner on chain 9, a cam 31 on chain 10, actuates lever 38, and the latter through pitman 37 releases chain 9 thus carrying its runner member out of sight. As the runner reaches third base, stop lever 48 is actuated through its pitman 47 and bell crank 26 and push button, thus starting chain 11 which carries its runner around over the third base and down to home. As the runner on chain 11 relays or takes its place on third base, a cam 31 on chain 11, acting against shoe 44 70 on stop lever 44, releases chain 10 thus permitting it to carry its runner out of sight. As the runner from third to home reaches home it immediately passes over home and then retires, there being no stop shoulder on the chain to hold it exposed. If one or more of the bases were filled and a hit made, the push buttons controlling chain 8, and the chain or chains to advance the runner or runners, would be simultaneously operated 80 so that the runners would advance simultaneously. If the bases were filled and a home run made, all the push buttons would be depressed simultaneously and held until the runner on third reached home. By that 85 time the runner from home to first will have reached first and disappeared. The push button controlling the chain 8 should then be released. After the runner on first reaches second and disappears, the button 90 controlling chain 9 should be released and so on until the last runner has completed the circuit of bases. If a runner should be caught between bases, this movement can be reproduced by pressing the button to start 95 the runner member toward the next base, and after the chain has been released from its stop lever, the handle 7² on the idle sprocket 7¹ on which the moving chain is mounted, is then grasped by the operator, 100 and he can by turning the handle move the chain which is free to slip with the runner member thereon forward or back, and have it disappear at the base on which the runner is put out, or show over the base which the 105 runner may retain or make. With this arrangement all of the runners are under the positive control of the stop mechanism, and by proper manipulation of the latter, the 110 runners can be made to reproduce the movements of a single runner, or the four of them at one time.

To reproduce the movements of the ball over the field, I provide two members 50 and 51, one of which (50) is preferably a sphere representing the ball and located at the front of the field, and the other a controlling member 51, being located at the rear. The ball 50, at the front, is secured to two cords 52, shown in dotted lines in Fig. 115 2, which latter are wound at their ends on the reels 53, located adjacent the upper edge of the supporting frame 1, near the corners thereof. The ball controlling member 50¹ is similarly connected to the cords 54, shown in full lines in Fig. 2, the opposite ends of said cords being wound around the reels 55. The reels 53 and 55 are secured to a shaft 120 125

56, journaled in the supporting frame 1, the reels 53 being at the front, and the reels 55 being at the rear of same. Fixed to the rear of each reel 55 or to the rear end of 5 each shaft 56, is a reel 57 carrying a cord 58, provided at its free end with a counter-weight 59. The cord 58 is wound on the reels in a direction opposite that of the cords 54, so that as the ball member 50 rises 10 or falls, the weight 59 will wind up or let out the cords 54, and as it moves sidewise the cords will wind up on the reels toward which the ball member is moving and unwind from the other, the weights 59 being 15 just sufficient to maintain the cords under proper tension.

Secured to the ball member 50, is the tension cord 55, shown in dotted lines in Fig. 2, and secured to the controlling member 50^a, 20 is the tension cord 56, shown in full lines in Fig. 2. These tension cords pass downwardly and are wound respectively on the reels 57 and 58, the former being at the front and the latter at the rear of the supporting frame 1. Each reel 57 and 58, has a smaller reel 59^a secured thereto on which the cords 60 are wound, which carry the counterweight 61, the cords 60 being wound in a direction opposite that of the cords 55—56, 30 so that the counterweights will always hold the tension cords taut. With this arrangement it will be seen that the ball member 50 is always directly opposite the controlling member 50^a. The latter is in the form of a 35 handle, so as to be readily grasped and manipulated, and by moving it in any direction in which the ball may take, the ball member will follow, so that by proper manipulation of the ball control at the rear, 40 the exact movements of the ball will be produced at the front in full view of the audience.

Instead of using reels for the ball and ball controlling cords I may use the funnel shaped tubes shown in Fig. 7. These tubes open respectively at the front and rear of the board, and the free ends of the two cords 52 and 54, are connected to a counter-weight 59^b, the funnel shapes of the tubes, 50 permitting free and unrestricted movement of the cords over the opposite faces of the board. The reels 57—58 and 59^b are carried by the carriage 62 which is connected to the counterweighted foot lever 63, shown 55 in Fig. 6. By placing the foot on the treadle of lever 63 and pushing down, the carriage and its reels will be moved outwardly, thus carrying the outer tension cord 53 and also the ball member away from the field and 60 producing the effect of a fly ball or a pitched high or low ball. By removing the foot from the treadle, the weight restores the parts to their normal position.

The ball member 50, is provided on its

rear face with a spring wire 51^a projecting 65 toward the board and operates as a flexible stop to prevent the ball swinging toward the board. It is made flexible so that in its movements over the field, it will bend or yield and pass over obstructions, such as a 70 runner member, or the raised outfield without interfering with the position or movements of said runner members, or obstructing the free movements of the ball member.

The out fielders are represented by members 64 of any size and shape, each secured to two flexible cords 65, each of which is mounted on a reel 66, the shaft of each of which passes through the frame and is provided at rear of the latter with similar 80 reels 67 around which the tension cords 68 carrying the counterweights are wound. By manipulating these counterweights the fielder members may be moved, to indicate the general movements of the fielders. 85

In Figs. 24 and 24^a, I have shown a member 4^a adapted to be bodily relayed from base to base by the runner members 4, and when used they are exposed and represent the runner members. Each is numbered to 90 represent a player, which member is exposed while the player is on a base and in advancing from one base to another, and each consists of three connected plates or disks 69—69^a and 69^b properly separated 95 and spaced, so that the runner members 4 which are in the higher plane, may enter between the plates 69 and 69^a while those in the lower plane may pass between the plates 69^a and 69^b. These plates are connected at one corner only and if they be circular, at one point only, so that the runner member 4 can freely enter and leave the member 4^a. Located between each pair of plates 69—69^a and 69^b, is a semi-elliptic 100 spring 70, each of which is secured at one end only to one of said plates, the two springs being located at right angles to each other as shown. When these members 4^a are used, the runner members 4 are provided on the upper faces with stops or abutments 71 separated sufficiently to permit the spring to enter lengthwise between them and be engaged by the side edges of the bowed portion of the springs, so that during the movements of the runner members 4, the members 4^a will be carried by the latter and exposed to view all the time. When the runner member 4 comes to a stop over a base, the spring yieldingly holding the 110 member 4^a on the runner member will be 115 parallel with the plane of the direction of movement of the next succeeding or relaying runner member, while the other spring will be at right angles and so disposed as 120 to permit the relaying runner member 4 to enter. When the relaying running member 125 has entered the member 4^a, its stops 71 en-

gage the side edges of the spring 70, hence when the runner member which is being relayed starts up so as to move out of sight, the relaying runner member holds member 5 4^a against movement, and when said relaying member moves toward the next base the member 4^a is carried thereon. In this way it is carried from the home plate around the bases and back to the home plate with 10 its indicating number exposed during the whole of the movement, and indicating to the audience the player on the base. If the runner should be put out on a base, say first, the member 4^a will disappear with the 15 runner member 4 to which it is attached and be removed from the latter by hand. If safe, the runner member 4 from first to second will upon being released, slide under the bottom spring of the bodily relay 20 member 4^a, after which the runner member from home to first will be automatically tripped and allowed to pass out of the bodily relay member 4^a. The latter is then placed for movement from first to second, 25 where it will be picked up by the runner member from second to third and so on.

With this apparatus an operator standing at the back of the board can, with one hand control the movements of the runner 30 members, and with the other hand move the ball controlling member in such a manner that any combination of plays and ball movements may be accurately portrayed at the front of the board.

35 Various changes might be made in the details of construction of my invention without departing from the spirit thereof or limiting its scope and hence I do not wish to restrict myself to the precise details here- 40 in set forth, but,

Having fully described my invention what I claim as new and desire to secure by Letters-Patent, is:

1. The combination of a representation of 45 a base ball field, the infield of which is in a different plane from the outfield, and mechanically controlled runner members adapted to be exposed over the infield when advancing and be concealed under the 50 field while returning to their starting points.

2. The combination of a representation of a base ball field, a runway intermediate the infield and outfield and separating them 55 and mechanically controlled runner members adapted to be exposed over one of said fields when advancing and be concealed under one of said fields while returning to their starting points.

3. The combination of a representation of a base ball field, the infield of which is in a plane behind the outfield, endless carriers located under the outfield and runner members carried by said carriers and adapt-

ed to project over the infield when advancing and be concealed under the outfield during their return movement.

4. The combination of a representation of a base ball field, an endless carrier between each two bases, and runner members 70 carried by said carriers and adapted to project over the infield when advancing and be concealed under the outfield during their return movement.

5. The combination of a representation of 75 a base ball field, an endless carrier between each two bases, a runner member on each carrier and means whereby a carrier is automatically released by the movements of a carrier in advance.

6. The combination of the representation of a base ball field, of a motor, gearing continuously driven by said motor, a series of endless carriers each having clutch connection with said continuously driven gearing, 80 and a runner member on each carrier.

7. The combination of a representation of a base ball field, a motor, a series of endless carriers connected with the motor, a runner member on each carrier, and means whereby 90 the several carriers may be actuated simultaneously by the motor, to carry their runner members to the bases next in advance and then back to their starting points without altering the direction of movement of the 95 carrier.

8. The combination of a representation of a base ball field, a series of endless carriers, a runner member carried by each, a motor, 100 gearing connecting the several carriers with the motor, and stop mechanism for each carrier.

9. The combination of a representation of a base ball field, a series of endless carriers, a runner member carried by each, a motor, 105 gearing connecting each carrier with the motor, slip clutch mechanism for each carrier constituting a part of said gearing, and a stop mechanism for each carrier.

10. The combination of the representation 110 of a base ball field, a series of endless carriers, means for driving them, a clutch constituting a part of said driving means, stop mechanism for each carrier and manually operated means for actuating said stop 115 mechanism.

11. The combination of a representation of a base ball field, a series of endless carriers, a runner member carried by each, means for driving them, a slip clutch for 120 each carrier constituting a part of said driving means, stop mechanism for each carrier, and means on several of the carriers for automatically actuating the stop mechanism of the carrier next behind.

12. The combination of a representation of a base ball field, a series of endless carriers, a runner member carried by each, means

for driving them, a slip clutch for each carrier constituting a part of said driving means, stop mechanism for each carrier, means on several of the carriers for automatically disconnecting the stop mechanism of the carrier next behind, and manually operated means for each stop mechanism.

13. The combination of the representation of a base ball field, an endless carrier between each two bases, a runner member on each carrier, the said runner members on the next adjacent carriers being located in different planes whereby they may pass each other at the turning points, and means for actuating the several carriers.

14. The combination of the representation of a base ball field, an endless carrier between each two bases, a runner member projecting laterally from each carrier and concealed by the field during one half of its movement, and means for actuating the several carriers collectively or independently.

15. The combination of the representation of a base ball field, an endless carrier between each two bases, a runner member projecting laterally from each carrier and concealed by the field during one half of its movement, means for actuating the several carriers, and means whereby a carrier may be released by the movement of the carrier in advance of the same.

16. The combination of the representation of a base ball field, an endless carrier between each two bases, means common to all of the carriers for driving the same, stops on the carriers, stop mechanism for engaging said stops and means for actuating said mechanism to release the carriers.

17. The combination of a representation of a base ball field, endless carriers between each two bases, means common to all of the carriers for actuating them, stops on the carriers, stop mechanism for engaging said stops and means carried by the carriers for automatically releasing the stop mechanism of the carrier next behind.

18. The combination of a representation of a base ball field, endless carriers between each two bases, means common to all of the carriers for actuating them, stops on the carriers, stop mechanism for engaging said stops, means on the carriers for automatically releasing the stop mechanism of the carrier next behind and manually operated means for actuating said stop mechanism singly or collectively.

19. The combination of a representation of a base ball field, a series of drive wheels, an idle wheel for each drive wheel, endless carriers each mounted on one drive wheel and one idle wheel, mechanism common to all of the drive wheels for actuating them, the said mechanism including a friction clutch for each drive wheel, stop mechanism

for holding the carrier against movement, means on the carriers for automatically releasing the stop mechanism of the carrier next behind, and manually operated means for each stop mechanism.

20. The combination of the representation of a base ball field, an endless carrier located between each two bases, a runner member on the carrier between the first and second bases, a plurality of runner members on each of the other carriers, mechanism, including a clutch for actuating each carrier and stop mechanism for locking the carriers against movement.

21. The combination of the representation of a base ball field, an endless carrier between each two bases, stop mechanism for the several carriers and means whereby the carriers are automatically released from the stop mechanism by the one next in advance.

22. The combination of a representation of a base ball field, endless carriers located intermediate the bases and runner members on said carriers which are automatically released from base to base.

23. The combination of a base ball field representation, a ball member on the front of the field, flexible devices carrying said ball member and diverging toward the top of the outfield, a ball control member, flexible devices carrying same and diverging toward the top of the outfield, and means connecting the flexible devices carrying said ball and ball control members whereby they are caused to move in unison in the same direction.

24. The combination of a ball field representation, a ball member at the front, a ball control at the rear, flexible devices carrying said ball member and ball control and extending toward the outfield from each member, means connecting said flexible devices at their outer ends whereby said members are caused to move in the same direction and the same distance, a tension member for the ball member, and a tension member for the ball control member.

25. The combination of a ball field representation, a ball member at the front, a ball control member at the rear, flexible devices carrying said members, connected reels located adjacent the outer limits of the outfield near the top of the latter, the said flexible devices being secured to the reels, and a counterweight suspended from each reel, the construction being such that the ball member at the front follows the movements of the ball control at the rear.

26. The combination of a ball field representation, connected reels located adjacent the upper outer margin of the outfield, a flexible device located at the front and carrying a ball member, the ends of said flexible device being secured to the reels, a flex-

ible device located at the rear and carrying a ball control member the ends of said latter flexible device being also secured to said reels, and a tension member for each connected reel.

27. The combination of a ball field representation, connected reels located adjacent each upper corner of the outfield, a flexible device at the front and one at the rear of the field, each secured at its ends to the said reels, a ball member secured to the flexible member at the front, a ball control secured to the flexible member at the rear, a tension device for each reel, a tension device for the ball member, and a tension device for the ball control.

28. The combination of a ball field representation, a flexible device at the front and one at the rear, the two flexible devices being connected at their ends so that they will move in the same direction in unison, a ball member secured to the flexible device in front, a ball control secured to the flexible device at the rear, tension means for the connected ends of the two flexible devices, a tension device connected to the ball member, and a tension device connected to the ball control.

29. The combination of a ball field representation, a ball member, diverging flexible members, from which the ball member is suspended, the position of the ball being controlled by varying the lengths of the supporting members between fixed points and the ball member, and means for moving the ball member toward and away from the field.

30. The combination of a base ball field representation, a ball member, two flexible diverging members from which the ball member is suspended, the position of the ball being regulated by varying the lengths of the supporting members between fixed points and the ball member, a tension member connected to the ball member and extending downwardly, and means for moving said tension member toward and away from the field.

31. The combination of a base ball field representation, fielder members supported on diverging flexible members, reels supporting the ends of said flexible members, and tension devices for the reels.

32. The combination of a reproduction of a base ball field, runner members adapted to move between each two bases, and a bodily relayed member adapted to be picked up by the succeeding runner member.

33. The combination of a reproduction of a base ball field, mechanically controlled movable runner elements which relay from base to base and a bodily relayed member

adapted to be picked up and carried by the next succeeding runner member.

34. The combination of a reproduction of a base ball field, an endless carrier between each two bases, a runner on each carrier and a bodily relayed member adapted to be picked up and carried by the next succeeding runner member.

35. The combination of a reproduction of a base ball field, an endless carrier between each two bases, a runner member on each carrier, automatic mechanism actuated by the movements of a carrier and controlling the movement of a carrier at the rear and a bodily relayed member adapted to be picked up and carried by the next succeeding runner member.

36. In a game apparatus the combination of a series of endless carriers, power driven means, including a clutch, for actuating said carriers and a hand actuated device for each carrier whereby the movements of a player caught between bases may be reproduced.

37. In a game apparatus the combination of a series of endless carriers, a motor, gearing connecting each carrier and the motor, clutch mechanism between the motor gearing and each carrier, and a hand actuated device connected with each carrier whereby the movements of a player caught between bases may be reproduced.

38. In a game apparatus the combination of a series of endless carriers, a runner member on each, a motor, gearing connecting each carrier with the motor, slip clutch mechanism for each carrier constituting a part of said gearing, stop mechanism for each carrier and hand operated mechanism for each carrier whereby the movements of a runner caught between bases may be reproduced.

39. The combination of a base ball field representation, a ball member at the front of the field, the said ball member having a rearwardly projecting flexible support adapted to contact with the field, and flexible devices carrying the ball member.

40. The combination of a reproduction of a base ball field, a runner carrier between each two bases, and a runner on each carrier, the runners adapted to be automatically relayed and return to the starting points by the movement of the carrier next in advance.

In testimony whereof, I have signed this specification in the presence of two subscribing witnesses.

PAUL C. OSCANYAN.
